UNITED STATES PATENT OFFICE.

JOHN KRODER, OF NEW YORK, N. Y.

EXTENSION CURTAIN-POLE.

1,082,478.

Specification of Letters Patent. Patented May 20, 1913.

Application filed February 27, 1912. Serial No. 680,192.

To all whom it may concern:

Be it known that I, JOHN KRODER, a citizen of the United States, and a resident of the city of New York, borough of Manhattan, in the county and State of New York, have invented a new and Improved Extension Curtain-Pole, of which the following is a full, clear, and exact description.

The object of the invention is to provide a new and improved extension curtain pole, more especially designed for use between the jambs of doors or windows, and arranged to permit of conveniently placing the telescoping pole sections in position on supporting brackets and locking the said pole sections on the said brackets to prevent accidental disengagement.

For the purpose mentioned use is made of supporting brackets provided with bosses having peripheral retaining lugs and telescoping pole sections adapted to engage with their outer ends the said bosses, each pole section being provided at the outer end with a ferrule, the ferrule and the end of the pole section being provided with a bead and slots leading to the bead to allow of engaging the bead with the said retaining lugs.

A practical embodiment of the invention is represented in the accompanying drawings forming a part of this specification, in which similar characters of reference indicate corresponding parts in all the views.

Figure 1 is a side elevation of the extension pole as applied, parts being in section; Fig. 2 is an enlarged sectional side elevation of one of the pole sections and its bracket, the pole section being in position prior to being locked to the bracket, and the section being on the line 2--2 of Fig. 3; Fig. 3 is a cross section of the same on the line 3--3 of Fig. 2; Fig. 4 is a cross section of the same on the line 4--4 of Fig. 2; Fig. 5 is an enlarged sectional side elevation of the outer portion of a pole section with the ferrule in position thereon and prior to forming the bead and slots; and Fig. 6 is a side elevation of the same with the bead and slots formed on the ferrule and pole sections.

The curtain pole is formed of two tubular pole sections A and A', of which the section A' telescopes in the section A and the outer ends of the said pole sections A and A' are supported on attaching brackets B, B' secured to the jambs of the door or window on which the curtain pole is to be used. Each bracket B, B' is provided with a

struck-up boss B² provided on its peripheral face with struck-up retaining lugs B³, preferably two in number, and located diametrically opposite each other, as plainly indicated in Fig. 3.

The outer end of each pole section A, A' is provided with a ferrule D having a flange D' bent inwardly against the inner surface of the end of the section A or A', so that the end of the corresponding pole section A or A' is confined between the ferrule D and its flange D', as will be readily understood by reference to Fig. 2. The pole sections A and A' are preferably made from flat sheet metal, bent into a tube having a lengthwise split at the meeting edges of the sheet (see Fig. 4), and by providing the ferrule D with the inturned flange D' the split outer end of the tube section A or A' is firmly held in place, without danger of the edges at the split overlapping or bending inward, thus maintaining the pole section A or A' in tubular form. After the ferrule D is locked in position on the end of the pole section A or A', the ferrule D and the end of the pole section A or A' is provided with an annular bead E and slots F are cut from the outer edge of the pole section A or A' inwardly to the rear wall of the bead E, as plainly shown in Fig. 6, to permit of engaging the pole section A or A' with the boss B² and with the slots F in register with the lugs B³ (see Figs. 2 and 3) to finally bring the bead E in register with the said lugs to allow turning of the pole section A or A' with a view to engage the bead E with the lugs B³ and thus hold the pole section A or A' against disengagement from the corresponding bracket B or B'.

The bead E is provided intermediate the slots F with an inwardly-extending bend or stop lug G to limit the turning movement of the pole section A or A' on the boss B² of the corresponding bracket B or B'. The inner end of the pole section A is preferably provided with a ferrule H similar to the ferrule D but without a bead or slots, the said ferrule H maintaining the split pole section A in tubular form so as to prevent the pole section from opening along the split. The inner end of the other pole section A' needs no ferrule as it fits inside of the section A and consequently is not liable to open along the split.

It is understood that the telescoping pole sections A and A' can be readily placed in

engagement with the boss B² of the brackets B and B' at the time the slots F register with the lugs B³, and then the pole sections A and A' are given about a quarter turn, that is, until the said lug G abuts against one of the retaining lugs B³, it being understood that the said retaining lugs B³ now extend within the annular bead E and consequently hold the pole section A or A' against disengagement in the direction of the length of the pole. It is further understood that the ferrule D not only holds the meeting edges of the split pole section A or A' in position but also reinforces the outer end of the pole section thus allowing the formation of an exceedingly strong reinforced bead E, and the inwardly-bent flange D' of the ferrule D provides a smooth finished end of the pole section.

Having thus described my invention, I claim as new and desire to secure by Letters Patent:

1. An extension curtain pole, comprising supporting brackets provided with attaching flanges and bosses integral with the flanges, the bosses having struck-up retaining lugs, and split pole sections telescoping one in the other and adapted to engage at their outer ends the said bosses, each split pole section being provided at its outer end with a ferrule having an inwardly-bent flange for receiving the outer arm of the pole section between the ferrule and its flange, the said ferrule and pole section being provided adjacent the inner end of the said flange with an annular bead, the said ferrule, its flange and the pole section being provided with slots leading to the said bead for the passage of the said boss lugs to engage the latter with the bead and thereby lock the pole section in place on the corresponding bracket.

2. An extension curtain pole, comprising supporting brackets provided with bosses

having peripheral retaining lugs and telescoping pole sections adapted to engage with their outer ends the said bosses, each pole section being split lengthwise and being provided at its outer end with a ferrule, the ferrule and each of the pole sections being provided with a bead and slots leading to the bead, to allow of engaging the bead with the said retaining lugs, and a stop lug integral on the bead intermediate the said slots to limit the turning motion of the pole section.

3. An extension curtain pole, comprising supporting brackets provided with retaining flanges and bosses integral with the flanges, the bosses having struck-up retaining lugs, and split pole sections telescoping one in the other and adapted to engage at their outer ends the said bosses, each split pole section being provided at its outer end with a ferrule having an inwardly-bent flange for receiving the outer terminal of the pole section between the ferrule and its flange, the said ferrule and pole section being provided adjacent the inner end of the said flange with an annular bead, the said ferrule, its flange and the pole section being provided with slots leading to the said bead for the passage of the said boss lugs to engage the latter with the bead and thereby lock the pole section in place on the corresponding bracket, and a top lug formed by bending a portion of the bead inward at a point between the slot to limit the turning motion of each pole section on the corresponding boss.

In testimony whereof I have signed my name to this specification in the presence of two subscribing witnesses.

JOHN KRODER.
